UNITED STATES PATENT OFFICE.

GEORGE S. HILL, OF BEVERLY, MASSACHUSETTS, ASSIGNOR TO UNITED SHOE MACHINE COMPANY, OF PATERSON, NEW JERSEY, A CORPORATION OF NEW JERSEY.

BENDER-ACTUATING MECHANISM FOR BLINDSTITCH SEWING-MACHINES.

1,113,628.

Specification of Letters Patent. Patented Oct. 13, 1914.

Application filed December 30, 1912. Serial No. 739,302.

To all whom it may concern:

Be it known that I, GEORGE S. HILL, a citizen of the United States, residing at Beverly, in the county of Essex and State 5 of Massachusetts, have invented certain Improvements in Bender-Actuating Mechanisms for Blindstitch Sewing-Machines, of which the following description, in connection with the accompanying drawings, is a 10 specification, like reference characters on the drawings indicating like parts in the several figures.

This invention relates primarily to bender actuating mechanisms for blindstitch sewing machines and particularly for those machines of the type known to the trade as buttonhole finishing machines, which are commonly used for gathering together and binding down upon the inner or unexposed 20 face of a buttonhole piece the stay cord and thrum ends left by the buttonhole sewing machine.

An essential element of machines of the class to which this invention relates is a 25 bender which is actuated to form successive bends or folds in the material and to present the bent material in the path of a reciprocating needle for the formation of stitches. Considering the character of the work to be 30 performed by a machine for finishing buttonholes in relatively thin leather such as is used for the uppers of light weight shoes—a kind of work for which the present invention is particularly intended—it is 35 obvious that the bender and its actuating mechanism must be very accurately adjusted in its relation to the needle and must be such that the bender will not, while in use, get out of proper position with relation to the 40 needle since the bender must be brought at each bending stroke very close to but at a predetermined distance from the needle, which should pass through the shoe upper or other thin material of the buttonhole 45 piece from the inner side and out at the same side of the material without penetrating or becoming visible upon the opposite or exposed side.

In the most generally known buttonhole 50 finishing machine, the bender is actuated yieldingly through a long line of connections extending from that end of the machine which is opposite to the operating point up

through a goose-neck and along substantially the entire length of the machine to 55 the bender itself. This type of bender actuating mechanism can not be employed with success in machines which operate at high speed.

Therefore, a primary object of the present 60 invention is to provide, for actuating the bender of a machine of this general class, a novel mechanism which shall operate with greater certainty and efficiency and at the same time at a higher speed than any yet 65 available to the trade.

An important characteristic of the preferred embodiment of the invention is that the connection between the bender and its actuator, upon the driving shaft or other 70 source of power, comprises only a few parts which move the bender unyieldingly in both directions although it is contemplated that the invention may be utilized in a machine in which the bender can yield relatively to 75 its actuator.

More specifically, a feature of the invention comprises the provision of a positively acting linkage between the bender or bender carrier and its actuator and, preferably, the 80 parts of this linkage are so located and proportioned that the bender, starting from raised or inoperative position, is given a continuous movement first to bring it into engagement with the work and then to perform the actual bending of the material, after which the bender is held in operative position, with the material fully bent, and in substantially fixed relation to the path of the needle for a considerable portion of each 85 cycle of operations. This dwell of the bender is designed to occur while the needle is entering the bent material and while it co-operates with the shuttle to form a stitch and thereafter to continue until the needle, 90 in its retracting stroke, reaches approximately the point where its eye is entering the material.

Another feature of the invention comprises a construction in which the linkage, 100 through which the bender is actuated, is driven by an eccentric member, preferably an ordinary eccentric, upon the driving shaft whereby cams are eliminated so that the machine, and particularly the bender, may be 105 driven successfully at high speed.

In addition to the features above specifically referred to, the present invention comprises certain combinations and arrangements of parts and particular details of construction hereinafter described and claimed.

Referring to the accompanying drawings, Figure 1 is an end elevation, partly in section, of a buttonhole finishing machine of a known type which embodies the bender actuating mechanism of the present invention in its preferred form, the parts of the machine being shown, with the bender raised, in position for the entrance of the work; Fig. 2 is a view similar to Fig. 1, showing the bender in operative position with the needle just about to leave the work on its retracting stroke; Fig. 3 is a plan view of the machine as shown in Fig. 2; and Fig. 4 is a diagrammatic view on a larger scale, showing successive positions of the bender and the several elements of its actuating mechanism.

As illustrated, the invention is embodied in a machine of the particular type shown and described in U. S. Patent No. 1,080,341, dated December 2, 1913, granted upon applicant's application, although obviously the invention in its broader features is not limited to use in a machine of that specific type. Accordingly, the parts of the machine which coöperate with the bender and its actuating mechanism will be only briefly described since they may be and preferably are arranged in substantially the manner illustrated in said prior application:

In the drawings, a hollow case 12, within which most of the operative parts of the machine are inclosed, serves as a table or support for the work which is fed through the machine from right to left. A recess or slot 14 is provided in the upper surface of the work table to receive the bent material, as shown in Fig. 2, and this slot may be, as usual, open bottomed at the operating point, i. e., directly below the bender. Other parts illustrated comprise a presser foot 16, pivoted at 18 in a hollow projection 20 which rises from the work support 12, a feed dog 22, a thrum gatherer 24, a needle 26 reciprocating in a horizontal plane parallel to and below the work supporting surface, and a shuttle 28 which coöperates with the needle in the formation of the stitches.

Referring now particularly to the bender and its actuating mechanism, to which the present invention specifically relates, the bender 30 may be clamped rigidly to its carrier 32 by means of a screw 34 which draws together the divided parts of a split bearing at the forward end of the carrier. The position of the bender relative to the path of the needle may be preliminarily adjusted by a screw 36. The bender carrier 32 is preferably in the form of a bell crank lever pivoted upon the same axis 18 as the presser foot

16 and connected at 38 to a link 40. The opposite end of link 40 is connected through pivot 42 with the connecting rod 44 which is driven from an eccentric 46 secured to the driving shaft 48. This shaft 48 is preferably rotated at a uniform speed but the parts of the linkage described are so located, arranged and proportioned that, as illustrated particularly in Fig. 4, the motion imparted to the bender 30 is variable.

The numerals 1 to 6 in Fig. 4 indicate successive positions of the center of eccentric 46, the lower end of bender 30 and certain elements of the linkage which connect them. When the parts are in the position designated 1, which is the position shown in Fig. 1 and by full lines in Fig. 4, the bender occupies its highest position and is farthest removed from the work. As the eccentric 46 rotates in the direction indicated by the arrow, the bender will move downwardly into engagement with the upper surface of the work and then its downward movement will continue while a fold or bend is being formed in the material and until the bender reaches its lowest position, designated 3, the several parts being indicated by dash lines in Fig. 4. During the latter portion of its operative stroke, the bender moves relatively slowly and while the eccentric 46 is moving from position 3 through position 4 to position 5, the pivot 42 connecting link 40 and rod 44 will move very nearly in an arc about the pivot 38 as a center, as illustrated in Fig. 4. Hence substantially no movement will be imparted to the bender carrier 32 for at least a third of a rotation of the driving shaft 48, with the result that the bender will hold the material properly bent for the needle as shown in Fig. 2. During this dwell of the bender, the needle will penetrate the bent material and coöperate with the shuttle 28 in the formation of a stitch. The bender will start upwardly from its lowest position at about the time that the needle, in its retracting stroke, reaches the position where its eye is entering the material and hence the bender will release the material from pressure so that the thread will not be broken as the locking or shuttle thread is drawn into the material. After the bender has moved out of contact with the work, it will return quickly to its highest position and the cycle of operations above described will be repeated, the work being fed forward while the bender is raised.

It will be noted that with the construction and arrangement of parts illustrated and described the bender is given a movement, the speed of which is so graduated that the bender will coöperate in the desired manner with the needle and other operating parts and yet it is actuated and controlled positively and by simple mechanism, such as an eccentric and short, direct connections

to the bender, a construction which is particularly adapted for use in a high speed machine.

Having thus indicated the nature and scope of the invention and having described in detail, by way of illustration, one particular embodiment of the invention, what I claim as new and desire to protect by Letters Patent of the United States is:—

- 10 1. In a blindstitch sewing machine, the combination of a driving shaft, an actuator upon said shaft, a reciprocating needle, a bender movable substantially at right angles to the path of the needle to bend the material being operated upon for penetration by the needle, a bender carrier and a linkage positively connecting said actuator and said carrier to move the bender unyieldingly while bending the material.

15 2. In a blindstitch sewing machine, the combination of a driving shaft rotating at approximately uniform speed, an eccentric actuator upon said shaft, a reciprocating needle, a bender movable substantially at right angles to the path of the needle to bend the material being operated upon for penetration by the needle, a bender carrier and a positively acting linkage connecting said actuator and said carrier and constructed and operated not only to move the bender unyieldingly to and from operative position but also to hold the bender in that position for a substantial portion of each rotation of the shaft.

20 3. In a blindstitch sewing machine, the combination of a reciprocating needle, a bender movable at substantially right angles to the path of the needle to bend the material being operated upon for penetration by the needle, a pivoted bender carrier to which the bender is rigidly secured and mechanism for actuating the bender comprising a driving shaft rotating at approximately uniform speed, an eccentric actuator upon said shaft, a connecting rod one end of which is connected to said actuator, a link joining the opposite end of said rod to the bender carrier and a guiding link swinging about a

fixed pivot and connected to said rod and located and operating to cause the bender to move from inoperative to operative position with increasing speed and to remain in operative position and in a substantially constant position relative to the path of the needle for a substantial portion of each rotation of the driving shaft. 55

4. A buttonhole finishing machine having, in combination, a work support provided with a slot, means for feeding the work, stitch forming mechanism including a needle reciprocating beneath and substantially parallel to the upper surface of the work support, a driving shaft rotating at approximately uniform speed also located beneath the work support and extending in a plane at right angles to the line of feed and to the path of the needle, an eccentric actuator upon said shaft, a bender movable substantially at right angles to the surface of the work support and to the path of the needle to bend the material being operated upon into said slot and into the path of the needle, a bender carrier oscillating about a fulcrum parallel to the driving shaft and a positively acting linkage connecting said actuator and said carrier. 75

5. In a buttonhole finishing machine, a driving shaft, a reciprocating needle, a bender movable substantially at right angles to the path of the needle to bend the material being operated upon for penetration by the needle, a bender carrier, in combination with mechanism for positively actuating the bender comprising an eccentric 46 on said shaft, a connecting rod 44, a link 40 and a guide link 50 mounted upon a fixed pivot 54 and connected at 52 to the rod, substantially as described. 80 95

In testimony whereof I have signed my name to this specification in the presence of two subscribing witnesses. 90
